GLIDER

Morton Pearlstine, Cynwyd, Pa., assignor to The Bunting Company, Inc., Philadelphia, Pa., a corporation of Pennsylvania

Application August 17, 1955, Serial No. 37,532

Term of patent 14 years

(Cl. D15—11)

The characteristic features of the present design reside in the parts of the glider shown in solid lines.

I claim:

The ornamental design for a glider, as shown and described.
